UNITED STATES PATENT OFFICE.

JAMES A. CAMERON AND GUSTAF BIRGER BIRCH, OF BROOKLYN, NEW YORK, ASSIGNEES TO CAMERON MACHINE COMPANY, OF BROOKLYN, NEW YORK, A CORPORATION OF NEW YORK.

SURGICAL BANDAGE.

1,217,562.

Specification of Letters Patent. Patented Feb. 27, 1917.

Application filed March 3, 1916. Serial No. 81,810.

To all whom it may concern:

Be it known that we, JAMES A. CAMERON and GUSTAF B. BIRCH, both citizens of the United States, and residents of the borough 5 of Brooklyn, in the county of Kings, city and State of New York, have invented certain new and useful Improvements in Surgical Bandages, of which the following is a specification.

10 This invention relates to surgical bandages in general and more particularly to bandages that are sold to the trade in the form of rolls composed of single strips of material of desirable width.

15 It is well known that the material of which bandages are made is usually of an open mesh character so that the warp threads adjacent the edges of the bandage strip have a tendency to ravel from the 20 bandage. This is objectionable for the reason that it interferes with the work of the surgeon by entangling his fingers as he applies the bandage. In order to prevent this objectionable unraveling of the outermost 25 warp threads, it is customary in the art to remove a number of such threads from each 30 end of the bandage roll. This results in a considerable waste and an object of this invention is to substantially reduce the

The surgeon's bandage constituting this invention is severed from the web of material with an undulating cut so as to simultaneously destroy the continuity of the 35 warp threads adjacent to the cut and so as to leave a scalloped edge formed by weft threads of unequal length. The bandage is consequently of such a character that the edges thereof will not unravel since the 40 outermost warp threads are destroyed and the remaining warp threads are held in place by the scalloped edge formed by the weft threads of unequal length recurring at regular intervals.

45 In the drawing:

Figure 1 shows the undulating line of severance by which bandages embodying the invention are cut from the web of material.

Fig. 2 shows the effect of the undulating 50 cut with the severed warp threads still in place.

Fig. 3 shows the edge of the bandage in its completed form and with the severed warp threads removed.

Surgeons' bandages are ordinarily made 55 of soft, loose-textured fabric the edges of which are easily unraveled unless precautions are taken to prevent it. In this invention a web of bandage material, indicated at 1, is severed by means of an undulating cut 60 as at 2 whereby scalloped edges are formed by weft threads 3 of unequal length intermeshed with fragments of the severed warp threads 4 as is best shown in Fig. 2. The removal of the severed warp threads 4 65 leaves a scalloped edge formed of the remaining weft threads 3 alone which constitutes the finished article shown in Fig. 3.

By thus providing an edge composed of weft threads from which a number of warp 70 threads have been removed, the tendency of the edges to ravel is overcome. By, in effect, causing convex portions of the edge of one strip to project into concave portions of the edge of a contiguous strip in alternation, 75 the total number of threads which it is necessary to remove from the edges of the strip to prevent unraveling is diminished by one half.

The improved bandage strip can be 80 quickly and cheaply made and is more 85 slightly in appearance than bandages now in use not only because of the lessened amount of material in the projecting weft threads, but also because of the regular arrangement of the varying lengths of projecting threads.

What is claimed, is:

1. A surgeon's bandage comprising: a strip of material the edges of which are 90 scalloped and formed by weft threads of unequal length recurring at regular intervals and devoid of continuous warp threads.

2. A surgeon's bandage comprising: a strip of material the edges of which are 95 scalloped and formed by weft threads of unequal length recurring at regular intervals and devoid of warp threads of appreciable length.

3. A surgeon's bandage comprising: a 100 strip of material the edges of which are scalloped and formed by weft threads of unequal length recurring at regular intervals and devoid of warp threads.

4. A surgeon's bandage comprising: a 105 strip of material the edges of which are scalloped and the convex portions of which are formed of weft threads.

5. A surgeon's bandage comprising: a strip of material the edges of which are scalloped and the convex portions of which are composed of weft threads from which the warp threads have been removed.
6. A surgeon's bandage comprising: a strip of material the longitudinal edge threads of which have been removed, and the transverse edge threads of which present an undulating edge.
7. A surgeon's bandage having undulating side edges devoid of longitudinal threads.
8. A surgeon's bandage having side edges composed solely of unequally projecting ¹⁵ weft threads recurring at regular intervals.

Signed at New York in the county of Kings and State of New York this 1st day of March A. D. 1916.

JAMES A. CAMERON.
GUSTAF BIRGER BIRCH.
